UNITED STATES PATENT OFFICE.

GEORGE EDWARD HARDMAN, OF EAST HAM, LONDON, ENGLAND, ASSIGNOR TO CARI-BONUM COMPANY LIMITED, OF LONDON, ENGLAND, A CORPORATION OF GREAT BRITAIN AND IRELAND.

PAPER-FEEDING DEVICE.

976,735.

Specification of Letters Patent. Patented Nov. 22, 1910.

Application filed November 26, 1909. Serial No. 529,975.

To all whom it may concern:

Be it known that I, GEORGE EDWARD HARDMAN, a subject of His Majesty the King of Great Britain, and a resident of East Ham, 5 London, England, have invented a certain new and useful Improvement in Paper-Feeding Devices, of which the following is a specification.

This invention relates to improvements in 10 mechanism for feeding paper or other sheets to printing and like machines, and it relates particularly, though not exclusively, to feeding mechanism for rotary duplicating machines of the kind in which the sheets are 15 fed forward one at a time by means of a transverse rod covered with pads or tubes of corrugated rubber the said rod resting upon the pile of sheets and being reciprocated backward and forward for each revolution of the cylinder.

In mechanism for feeding single sheets to printing mechanism it has been proposed to employ reciprocating wheels each provided with pawl and ratchet mechanism whereby 25 the wheels were able to roll freely over the sheets during the backward reciprocation, but were prevented from turning during their forward reciprocation thus producing friction between their peripheries and the 30 uppermost sheet whereby the latter was fed forward. This pawl and ratchet mechanism was, however, open to various objections, and the object of the present invention is to provide an improved device whereby the rotation of the reciprocating feed-roller can be controlled in the manner described above.

According to this invention a reciprocating rubber covered feed-roller or feed 40 wheels suitably adjustable is or are provided with a friction clutch or clutches which can run free during the backward reciprocation but can bind during the forward reciprocation. Such clutch or clutches may be the ordinary free wheel ball or pawl wedging 45 devices.

In a preferred construction a roller is mounted loosely upon an axle that extends transversely across the machine above the pile of sheets, and that is secured at each 50 end, for example, to links, forming parts of any suitable mechanism for reciprocating the axle. At one end of the roller a ball-clutch is provided, one member of which is secured to or forms a part of the roller, the 55 other being secured to the stationary axle.

One of the parts of the clutch may consist of an inner circular roller or wheel, grooved on its periphery, and secured to the roller; the other part may consist of an eccentrically bored shell, which is fitted over the grooved inner roller or wheel, and is secured upon the axle. A race of varying widths is therefore formed between the inner clutch roller and the inner periphery of the eccentric shell; in this race a ball is inserted, the size of said ball being rather smaller than the greatest width of the race, but larger than the smallest width of said race. The result is that when the roller is reciprocated backward the ball moves toward the wider portion of the race, while when the roller is reciprocated forward the ball is forced toward the narrower portion of the race and consequently locks the roller from turning.

In the accompanying drawings is illustrated as an example one embodiment of the invention.

In these drawings: Figure 1 is a sectional elevation of one construction of feeding mechanism according to this invention applied to a rotary duplicating machine, some parts of which are shown also, and Fig. 2 is a sectional plan of same.

A is the feeding roller, B the fixed axle, and A', B' the clutch members, A' consisting of a grooved roller secured to the feeding roller A and B' consisting of an eccentrically hollowed shell secured to the axle B by means of a set-screw B².

In Fig. 1 the variation in the width of the race C is shown, a ball C' being shown therein. It will be seen that when the roller A is moved backward (or to the left) the part B' will not rotate and the part A' will rotate counter-clockwise thus tending to force the ball C' into the wider portion of the race C, but when the said roller is drawn forward, that is to say in the direction of the arrow (Fig. 1), the part A' will tend to rotate in the opposite direction—clockwise—and since the part B' is fixed, the ball will be forced into the narrower portion of the race C thus wedging between the parts A' and B' and preventing the former, and consequently the roller A, from moving, so that it will frictionally engage and draw forward the sheet of paper it is resting on. The part B' is provided with a pin B³ to prevent the ball from affecting the rotation of the roller A during its backward recipro-

cation. The roller A abuts at one end against a collar or boss B⁶ upon the axle B, and roughened or other rubber bands A³ preferably encircle the periphery of said roller to increase the frictional grip of the roller upon the uppermost sheet of the pile. Such bands are preferably movable longitudinally on the roller so that they may be adjusted for different widths of paper.

10 When the feeding roller according to this invention is applied to rotary duplicating machines it may be reciprocated by means of the known arrangement of links and levers as shown. In this reciprocating mechanism the link a is connected to the driving wheel (not shown) and operates an arm b mounted upon one end of a shaft b' which carries an arm c at each end. These arms c are each connected by means of links d' to slides d which are in turn connected to each end of the axle B by links d². The slides d reciprocate upon guide rods d³. The axle B may be fixed in the end of one of the links d² by means of a set screw d⁴.

15 20 25 26 What I claim is:—

A paper feeding device comprising a roller, elastic paper contacting bands carried by the same and adjustable thereon, an axle on which said roller is rotatably mounted, a hollow casing secured to the axle at 30 one end of the roller, a wheel secured to the roller at the same end and projecting into the casing said casing being bored eccentrically and coöperating with the wheel to form a race of varying width, a ball within 35 the casing and adapted to be engaged between the casing and the wheel so as to prevent the roller from rotating in one direction, a pin carried by the casing for rendering the ball inoperative when the roller is 40 rotated in the opposite direction and means for reciprocating the carrying axle.

In testimony whereof I have hereunto set my hand in the presence of two subscribing witnesses.

GEORGE EDWARD HARDMAN.
